VARIABLE SPACING MECHANISM FOR
TYPEWRITING MACHINES

Charles Clinton Peters, State College, Pa.

Application September 16, 1936, Serial No. 101,156

11 Claims. (Cl. 197—84)

This invention relates to new and useful improvements in typewriting and like machines, and more particularly to variable spacing devices and attachments therefor.

5 An objection common to the ordinary typewriter is that notwithstanding the different letters occupy unequal space upon the paper, the spacing of the machine during normal operation thereof is nevertheless uniform, and results in 10 relatively large gaps or spaces between the narrower characters such as i, I, f, l and t, while the larger or wider characters such as m, w, M, W and the like are unduly crowded or the characters are themselves deformed, thus rendering the 15 typewritten matter less readily legible and detracting from the appearance thereof.

The principal object of the present invention, therefore, is to provide a device or attachment for typewriting and like machines which is novel- 20 ly constructed and arranged to allot to the letters m, w, M and W a space greater than that afforded by normal operation of the typewriter, and to the letters i, I, f, l, t and the like a lesser space than that afforded by normal operation of 25 said typewriter.

Another object of the invention is to provide a device or attachment of the character set forth for typewriting and like machines which is operable independently of the escapement mechanism to control the movement of the carriage in 30 a predetermined ratio and thus vary the spacing of certain of the type characters in a line or lines of typewriting.

More particularly, the invention consists in 35 the features of construction, combinations of elements and arrangement of parts hereinafter set forth and shown in the accompanying drawings in which

Figure 1 is a view in perspective showing one 40 form of the present invention operatively associated with a typewriting machine;

Fig. 2 is a view in elevation showing a device or attachment made in accordance with the present invention;

Fig. 3 is an inverted plan view of a typewriting 45 machine embodying the present invention;

Fig. 4 is a diagrammatic view in section vertically through the disclosure of Fig. 3; and

Fig. 5 is a diagrammatic view illustrating cer- 50 tain features and details of the construction and arrangement of the present invention, together with the electric circuit for operating the same.

Referring now to the drawings, reference nu- 55 meral 1 designates generally a typewriting ma-

chine inclusive, as usual, of a base or frame 2, a carriage 3 and an escapement mechanism whereby advance of the carriage progresses step by step in response to depression of the keys and space bar. As shown in Fig. 3, the escapement mechanism of the typewriting machine illustrated in the drawings comprises the customary rack bar 4 which is meshed with a pinion 5 mounted for rotation with an escapement wheel 6. The step-by-step rotation of the escapement wheel 6 is controlled by means of pawls 7 and 8 which are alternately released in the usual manner by depression of the several keys 9 and space bar 10 to permit a corresponding traverse of the rack bar 4 and carriage 3, the latter being actuated by 15 means of the usual spring tension device 11.

Referring to Fig. 4 of the drawings, in the particular typewriting machine illustrated, alternate release of the pawls 7 and 8 is accomplished through a bridge piece 12 which is pivotally 20 mounted as at 13 and operatively connected to the pawl releasing mechanism through links 14 and 15, said bridge piece 12 being engaged by the projecting portion 16 on the type bar rods 17 and actuated downwardly or in counter-clock- 25 wise direction thereby as each type bar 18 moves in a clockwise direction into operative or writing position against the carriage 3 in response to depression of its key 9. Each of the keys 9 is mounted at the forward end of a key bar 19 30 which is pivotally mounted as at 20 and operatively connected to the lower end of one of the rods 17 by means of a stirrup or the like 21 and links 22 and 23 respectively, which are controlled by means of a spring 24, movement of the type 35 bars 18 and rods 17 being further controlled by a series of links 25, 26 and 27 as well as a spring 28 and counterweight or balance 29. Apart from the foregoing, the typewriting machine includes, of course, various other mechanisms which do 40 not enter into the invention and are therefore not illustrated or described.

As also shown in Fig. 4 of the drawings, cer- 45 tain of the key bars 19 have contact points or electrodes 30 secured at their undersides adjacent the forward ends thereof and these points or electrodes 30 are arranged to contact similar points or electrodes 31 at each depression of said key bars 19 by their keys 9, said points or electrodes 31 being suitably located on the base or frame 2 directly below said points or electrodes 30. In accordance with the present invention the keys 9 which actuate the type bars 18 for typewriting the letters m, w, l, t, f and i are pro- 50 vided with contact points or electrodes 30 and 31 55

arranged in the manner just described and these points or electrodes are connected respectively to one side of a solenoid 32 through a conductor 33 and to one terminal of a source of electricity 5 such as a battery or the like 34 through a conductor 35, the other terminal of said source of electricity 34 being connected to the other side of said solenoid 32 through or by means of a conductor 37. Thus it will be observed that when 10 each of the several keys 9 mentioned above is depressed to contact the points or electrodes 30 and 31 associated therewith an electric circuit will be completed through the solenoid 32, the purpose for which will be described in detail hereinafter.

In the present instance the solenoid 32 is secured by means of a bracket or standard 38 to a base member 39 which is in turn secured to the end plate 40 of the carriage 3 at one side of the 20 typewriting machine for movement with said carriage, and an armature 41 is pivotally mounted as at 42 in brackets 43 secured to the upper face of said base 39, said armature being arranged for vertical movement into contact with the lower 25 end face of the core 44 of said solenoid 32 when the latter is energized, against the action of a leaf or other type of spring 45 which normally retains the armature 41 in the position shown in Fig. 2 of the drawings removed from contact with 30 said core 44.

A ratchet bar 46 having teeth 47 and 48 on the top and bottom side thereof respectively is slidably mounted in brackets 49 at the underside of the base member 39 for movement longitudinally thereof and the teeth 47 and 48 of said ratchet bar 46 are arranged for engagement alternately by teeth or pawls 50 and 51 respectively provided at the top and bottom edges of an opening or slot 52 in a depending leg portion 53 40 of the armature 41 through which the said ratchet bar 46 extends. The teeth 47 in the top side of the ratchet bar 46 are spaced at intervals equal to one-half the distance traversed by the carriage 3 at each actuation of the escapement 45 mechanism and the teeth 48 at the underside of said ratchet bar 46 are similarly spaced but arranged in staggered relation with respect to said teeth 47 in the top side thereof so that movement of the bar 46 at each energization of the 50 solenoid 32 is limited to a distance equal to the space between the teeth at either side of said ratchet bar 46 and one-half of the distance regularly traversed by the carriage 3 at each actuation of the escapement mechanism.

55 In accordance with the present invention, the rack bar 4 of the escapement mechanism is slidably mounted on the carriage 3 for relative longitudinal movement with respect thereto by means of pins or the like 54 and 55 secured in 60 any suitable manner into the opposite end faces of said rack bar 4 and slidably supported in collars or like members 56 and 57 which depend from and are permanently secured to opposite ends of said carriage. As shown in Figs. 1 and 65 2 of the drawings the outer end of the pin 55 is connected as at 58 to the lower end of a depending vertical leg portion 59 at the inner end of the ratchet bar 46 so that the latter is rigidly connected to the rack bar 4 for movement there- 70 with relative to the carriage 3, armature 41 and its base member or support 39. Thus it will be observed that the inter-engagement of the teeth 47 and 48 and 50 and 51 on the bar 46 and armature 41 respectively provide the only operative connection between the rack bars 4 and the

carriage 3 and therefore the sole means for controlling the relative longitudinal movement of one with respect to the other by means of which variable spacing may be allotted to different letter characters in typewriting.

5 In operation of the device, when the keys 9 for writing the letters m, w, M and W are depressed, two separate and distinct operations occur as follows. The projecting portion 16 on the particular type bar rod 17 depresses the bridge 12 and 10 releases the escapement mechanism allowing the rack bar 4 and carriage 3 to traverse a distance equal to uniform regular space afforded each letter under normal operation and use of the typewriter, and at the same time depression of 15 these keys 9 engages the points or electrodes 30 and 31 associated therewith to complete an electric circuit through the solenoid 32 thus raising the armature 41 to disengage the teeth 50 from the teeth 47 on the upper side of the ratchet and 20 engage the teeth 51 of said armature with the teeth 48 at the underside of the bar 46, the spring 45 returning the armature to its original position with the teeth 50 engaging the teeth 47 in the upper side of the bar 46 immediately pressure on 25 such key 9 is released and the circuit through the solenoid 32 broken.

From the foregoing it will be observed that during the interval between disengagement and re-engagement of the teeth 50 of the armature 41 30 with the teeth 47 of the ratchet 46 the connection between the latter and the base 39 is twice broken thus allowing relative longitudinal movement of the armature with respect to said base 39 and permitting the carriage 3, which is under 35 tension, to travel a further distance equal to one-half the distance of regular travel provided by operation of the escapement to provide the letters m, w, M and W with a space in a line of typewriting one-half again as great as that provided by operation of said escapement alone.

In the instance of the letters i, I, t, l and f where it is desired to provide spaces therefor which are less than the regular spacing afforded by operation of the escapement, the projecting 45 portion 16 on each of the rods 17 of the type bars 18 for writing these particular letters is removed or cut away so that actuation of the bridge piece 12 and release of the escapement will not occur when the corresponding keys 9 are depressed in 50 the usual manner, thus it will be seen that the only spacing allotted to these letters in a line of typewriting is provided by means of the solenoid 32 through which a circuit is completed by the contacts 30 and 31 to disengage the teeth 50 55 from the teeth 47 of the ratchet bar 46 in the manner previously described and permit traverse of the carriage 3 with respect to the writing point and rack bar 4 a distance equal to one-half the regular spacing provided for the letters in normal 60 operation of the typewriting machine whereby the particular letters mentioned are allotted a total space in a line of typewriting equal to but one-half that afforded by normal step-by-step 65 operation of the escapement mechanism.

In typewriting capital L, T and F which are located upon the same type bars 18 as the corresponding small letters it will be necessary to increase the half-spacing provided by operation of the solenoid 32 as just described by releasing 70 the escapement so that sufficient space in a line of typing may be afforded to these capital letters which are, of course, of substantially greater width than their small letters and inasmuch as the projecting portions 16 have been removed or 75

cut away from the type bar rods 17 as previously described, it will be necessary to effect independent operation of the escapement. In the present instance this may be accomplished by depressing the space bar 10 in the usual manner simultaneously with depression of the key 9 corresponding to L, T or F. Several suitable forms of mechanism may, however, be provided to accomplish this result depending upon the particular construction of the typewriting machine employed, and, for example, as shown in Fig. 4 of the drawings, an auxiliary bridge piece 60 is provided and pivotally mounted as at 61 at the rear of the bridge piece 12, said bridge piece 60 being normally retained in a substantially raised or horizontal position by means of a spring 62 which engages said bridge piece 12. As further shown in Fig. 4 each of the type bar rods 17 of the letters L, T and F is provided with a projection 63 in lieu of the projections 16 which have been removed or eliminated and these projections 63 are disposed at an elevation above the projections 16 and arranged to engage the auxiliary bridge piece 60 and actuate the same downwardly in a manner similar to actuation of the bridge 12 by said projections 16. As will be clearly seen from the drawings the auxiliary bridge piece 60 is freely movable with respect to the bridge 12 and normally has no connection with the escapement mechanism so that depression thereof by projections 63 when typing small l, t and f will be ineffective to release the escapement.

However in typing or printing capital L, T and F and in fact all capital letters when the customary shift key 64, which rocks about to pivot 64a, is depressed to elevate the carriage 3 through a series of links 65, 66 and 67, a stop 68 is actuated upwardly in slots 69 in the skirt of the bridge piece 12 by means of links 70 and 71 into the path of the auxiliary bridge piece 60 to preclude relative rotation thereof with respect to the bridge 12 and causing downward actuation thereof through engagement by the projections 63 to similarly actuate the bridge 12 and in turn release the escapement mechanism through the links 14 and 15 in the usual manner. Thus it will be observed that in addition to the one-half space provided by release of the ratchet bar 46 due to energization of the solenoid 32, capitals L, T and F, as in the case of the letters m, M, w and W, are, due to release of the escapement mechanism, provided with a space of one-half again as great as that afforded by operation of the escapement alone.

From the foregoing description of the invention it will be observed that the letters m, M, w, W, L, T and F are allotted a larger or wider space in a line of typewriting than the regular spacing afforded by the step-by-step operation of the escapement and the letters i, I, l, t and f are allotted a smaller or narrower space than that afforded by the escapement mechanism, while the remaining letters, numbers, and characters are allotted the regular spacing afforded thereby although any one or more of such other letters, numbers and characters may be provided with a greater or lesser space where desired by merely connecting the same into the solenoid circuit and eliminating or permitting release of the escapement mechanism in the manner previously described.

While in the foregoing description of the invention the additional space allotted letters m, M, w, W, L, T and F is described as one-half that afforded by the regular step-by-step operation

of the escapement, this fraction may obviously be made increased or decreased as desired by merely changing the spacing of the teeth 47 and 48 as compared with the total normal width of letters determined by the regular escapement mechanism. 5

While a specific embodiment of the invention has been illustrated and described herein, it is not intended that said invention shall be precisely limited thereto but that modifications and 10 changes necessary to its adaptation to typewriting machines of various forms may be incorporated and embodied therein within the scope of the annexed claims.

I claim:

1. A variable spacing mechanism for typewriting machines having a movable carriage and an escapement, a rack bar controlled by said escapement and normally connected to said carriage for movement therewith, a plurality of type actuating keys operable to release the escapement and effect regular step-by-step movement of said rack bar and carriage, and mechanism controlled by the operation of certain of said type operating keys operable to momentarily disconnect the 25 carriage from the rack bar and permit movement of the former a predetermined distance independently of the latter and said escapement.

2. A variable spacing mechanism for typewriting machines having a movable carriage and an 30 escapement, a rack bar controlled by said escapement and normally connected to said carriage for movement therewith; a plurality of type actuating keys operable to release said escapement and effect regular step-by-step movement of said 35 rack bar and carriage, a plurality of other type actuating keys inoperable to release the escapement, and mechanism controlled by the operation of certain of said first and second mentioned 40 type actuating keys operable to momentarily disconnect the carriage from the rack bar and permit traverse of the former a predetermined distance independently of the latter and said escapement.

3. A variable spacing mechanism for typewriting machines having a movable carriage and an escapement, a rack bar controlled by said escapement and normally connected to said carriage for movement therewith; a plurality of type actuating keys operable to release said escapement and effect regular step-by-step movement of said rack bar and carriage, a plurality of other type actuating keys inoperable to release the escapement, mechanism controlled by the operation of certain of said first and second mentioned type actuating keys operable to disconnect the carriage from the rack bar and permit traverse of the former a predetermined distance independently of the latter and said escapement, and means operative at will to also effect release of the 60 escapement and permit step-by-step traverse of the carriage and rack bar upon operation of predetermined type actuating keys in the second mentioned group thereof. 55

4. A variable spacing mechanism for typewriting machines having a movable carriage and an escapement, a plurality of type actuating keys, means connecting the escapement and the carriage, including a slidably mounted rack bar and an auxiliary escapement for controlling movement of said carriage relative to said rack bar, and means controlled by the operation of certain of said type operating keys operable to release said auxiliary escapement and permit movement of the carriage a predetermined distance 70 75

relative to the rack bar and independently of the first mentioned escapement.

5. A variable spacing mechanism for typewriting machines having a movable carriage and an escapement, a plurality of type actuating keys operable to release said escapement and effect regular step-by-step movement of said carriage, a plurality of other type actuating keys inoperable to release the escapement, means connecting said escapement and the carriage to permit regular step-by-step traverse thereof upon release of the escapement, including a slidably mounted rack bar and an auxiliary escapement for controlling movement of said carriage relative to said rack bar, and means controlled by the operation of certain of said first and second mentioned type actuating keys operable to release said auxiliary escapement and permit movement of the carriage a predetermined distance relative to the rack bar and independently of the first mentioned escapement.

6. A variable spacing mechanism for typewriting machines having a movable carriage and an escapement, a plurality of type actuating keys operable to release said escapement and effect regular step-by-step movement of said carriage, a plurality of other type actuating keys inoperable to release the escapement, means connecting said escapement and the carriage to permit regular step-by-step traverse thereof upon release of the escapement, including a slidably mounted rack bar and an auxiliary escapement for controlling movement of said carriage relative to said rack bar, means controlled by the operation of certain of said first and second mentioned type actuating keys operable to release said auxiliary escapement and permit movement of the carriage a predetermined distance relative to the rack bar and independently of the first mentioned escapement, and means operative at will to cause release of the escapement, including a slidably mounted rack bar and an auxiliary escapement for controlling movement of said carriage relative to said rack bar, means controlled by the operation of certain of said first and second mentioned type actuating keys operable to release said auxiliary escapement and permit movement of the carriage a predetermined distance relative to the rack bar and independently of the first mentioned escapement, and means operative at will to effect release of the escapement and step-by-step traverse of the carriage upon operation of predetermined type actuating keys in the second mentioned group thereof.

45 7. A variable spacing mechanism for typewriting machines having a movable carriage and an escapement, a plurality of type actuating keys, means connecting the escapement and the carriage, including a slidably mounted rack bar and an auxiliary escapement for controlling movement of said carriage relative to said rack bar, and energizable means controlled by the operation of certain of said type operating keys operable to release said auxiliary escapement and permit movement of the carriage a predetermined distance relative to the rack bar and independently of the first mentioned escapement.

8. A variable spacing mechanism for typewriting machines having a movable carriage and an escapement, a plurality of type actuating keys operable to release said escapement and effect

regular step-by-step movement of said carriage, a plurality of other type actuating keys inoperable to release the escapement, means connecting said escapement and the carriage to permit regular step-by-step traverse thereof upon release of the escapement, including a slidably mounted rack bar and an auxiliary escapement for controlling movement of said carriage relative to said rack bar, and energizable means controlled by the operation of certain of said first and second mentioned type actuating keys operable to release said auxiliary escapement and permit movement of the carriage a predetermined distance relative to the rack bar and independently of the first mentioned escapement.

9. A variable spacing mechanism for typewriting machines having a movable carriage and an escapement, a plurality of type actuating keys operable to release said escapement and effect regular step-by-step movement of said carriage, a plurality of other type actuating keys inoperable to release the escapement, means connecting said escapement and the carriage to permit regular step-by-step traverse thereof upon release of said escapement, including a slidably mounted rack bar and an auxiliary escapement for controlling movement of said carriage relative to said rack bar, energizable means controlled by the operation of certain of said first and second mentioned type actuating keys operable to release said auxiliary escapement and permit movement of the carriage a predetermined distance relative to the rack bar and independently of the first mentioned escapement, and means operative at will to cause release of the escapement and effect step-by-step traverse of the carriage upon operation of predetermined type actuating keys in the second mentioned group thereof.

10. In a typewriting machine having a movable carriage and an escapement, a rack bar controlled by said escapement, means connecting said carriage to said rack bar for movement therewith including an auxiliary escapement and mechanism operable to momentarily release said auxiliary escapement and disconnect the carriage from the rack bar to permit movement of the former independently of the latter and the escapement.

11. In a typewriting machine having a movable carriage and an escapement, a rack bar controlled by said escapement, a releasable connection between the rack bar and the carriage to normally effect conjoint movement thereof, and mechanism operable to release the connection between said rack bar and carriage and permit movement of the latter a predetermined distance independently of the rack bar and escapement.

CHARLES CLINTON PETERS. 60
